(57) **CLAIM**

The ornamental design for a mower cutting head unit assembly, as shown and described.

DESCRIPTION

FIG. 1 is a first perspective view of a mower cutting head unit assembly showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is an exploded view of the mower cutting head thereof.

The broken lines shown in the drawings depict portions of the mower cutting head unit assembly that form no part of the claimed design.

1 Claim, 9 Drawing Sheets
